UNITED STATES PATENT OFFICE.

CHARLES G. TATE, OF CHICAGO, ILLINOIS, ASSIGNOR, BY MESNE ASSIGNMENTS, TO EDWIN A. BENSON, OF CHICAGO, ILLINOIS.

CONSTRUCTION OF WHEELS.

1,170,706.

Specification of Letters Patent.

Patented Feb. 8, 1916.

Application filed August 4, 1913. Serial No. 782,846.

To all whom it may concern:

Be it known that I, CHARLES G. TATE, a citizen of the United States, residing at Chicago, in the county of Cook and State of Illinois, have invented a certain new and useful Improvement in the Construction of Wheels, of which the following is a specification.

My invention relates principally to wheels which are designed for automobiles, and has for its object to greatly simplify the construction of the said wheels, to materially increase their strength, and to largely increase the resiliency of the wheels without weakening the same.

My means of accomplishing the foregoing may be more readily understood by having reference to the accompanying drawings, which are hereunto annexed and are a part 20 of this specification, in which:

Figure 1 is a fragmentary view of a portion of a wheel constructed in accordance with my invention. Fig. 2 is a sectional view through the center of the hub. Fig. 3 is an enlarged detail view of the securing ring for holding the spokes in position. Fig. 4 is an enlarged fragmentary view of the outer end of the hub, part of the same being shown in section, to show clearly the 30 manner of fastening the inner ends of the spokes and of tightening the same.

Similar reference numerals refer to similar parts throughout the entire description.

As shown in the drawings, the hub consists 35 of a tubular portion 1, which is adapted to be secured to the outwardly projecting end of the box 2, which latter is provided with a brake drum 3 of the usual construction. The tubular member 1 is provided with an 40 outwardly extending flange 4, which is provided with a laterally extending peripheral flange. The brake drum 3, is secured to the said flange by means of bolts 5. These bolts can be any desired number to furnish the 45 requisite strength. In the outer end of the tubular member 1 I form a keyway 19, to which is fitted a key 6. A tubular member 7 is slidably but non-rotatably mounted upon the tubular portion 1 of the hub, the 50 key 6 being provided to prevent its rotation. It will be obvious that any number of these keys may be employed to furnish the required resistance to the torque.

The tubular member 7 is provided with 55 an outwardly extending flange 8, which has

cast or formed therewith a laterally extending peripheral flange which is provided with a plurality of holes 9, through which the spokes 10 pass. The spokes are provided at their inner end with circumferential grooves 11, as clearly seen in Fig. 5. A ring 12 is located inside of each of the laterally extending peripheral flanges formed on the flanges 4 and 8. Each ring is provided with a plurality of slots 13 and 14, the slots 13 65 being deeper than the slots 14, the reason for which will be hereinafter explained. Threads 15 are cut upon the tubular member 7, and, adapted to be engaged by internal threads cut upon a nut 16, which serves to 70 put a tension on the spoke.

The assembly of my wheel is as follows: The spokes 10, which are provided with upset heads 17 at their outer ends, which are adapted to engage the depressions formed 75 in the rim 18 of the wheel, are dropped into the rim and their inner ends extending inside the peripheral flanges formed on the flanges 4 and 8, in which position the rings 12 are dropped into place, the slots engaging the circumferential grooves 11 on the inner ends of the spokes. By making these slots alternately deep and shallow, I prevent the spokes coming in contact with each other when the tension is put upon them. 80 This latter result is accomplished by rotating the nut 16, which can be done by means of a spanner wrench, or if desired, it can be made hexagonal for other forms of wrenches. The tightening of this nut brings 85 its inner wall in contact with the end wall of the tubular portion of the hub, and the continued rotation draws the tubular member 7 outwardly, thereby tightening the spokes, the tension of which can be made as 90 great as is desired.

By this construction it is possible to furnish a device which when employed by an unskilled workman results in the production of a wheel which is perfectly true both 100 laterally and radially. The spokes can be drawn up to any tension and have present in them none of the weaknesses which are present in those spokes which employ threaded nipples at their outer ends.

My means of imparting an increased resiliency to the wheel will be more clearly observed in the assembled view. It will be observed that I have extended the spoke 105 outwardly on a true radius. Then it is bent 110

or curved in the swaged or up-set portion, which portion is calculated to provide a bending moment in excess of the tensile strength of a smaller portion. As this bend 5 on the spoke is made on the arc of a true circle, and is designed at too slight an angle to cause the least crystallization of the material, the result is that the wheel is constantly in a state of suspension, which materially increases the resiliency thereof.

Having described my invention, what I regard as new and desire to secure by Letters-Patent is:

1. In a wheel, a rim, a hub comprising a 15 tubular member having an apertured flange, a tubular member supported on one end of the hub, the second mentioned tubular member having apertures, spokes, each of said spokes having one of its ends secured to the 20 rim, the opposite ends of the spokes extending through the respective apertures of the tubular members, and having circumferential grooves providing shoulders, slotted rings engaging the shoulders of the spokes, 25 and means for holding the slotted rings in position.

2. In a wheel, a rim, a hub, a tubular member supported on the hub and having an apertured flange, spokes, each of said spokes 30 having a shoulder adjacent one end thereof,

said spokes extending through the apertures of the flange of the tubular member, a slotted ring adapted to engage the shoulders of the spokes, a nut positioned on one end of the hub, said nut adapted to engage the 35 ring for securing the spokes to the hub.

3. In a wheel, a rim, a hub, a tubular member having an apertured flange supported on one end of the hub, spokes of a less diameter than the area of the apertures, said 40 spokes extending through the apertures, each of said spokes having a head, slotted means coöoperating with the heads of the spokes for holding the spokes in position, and a nut for holding said slotted means in position.

4. In a wheel, a rim, a hub, a tubular member having an apertured flange, spokes extending through the apertures, means engaging one end of each of the spokes for 45 holding the spokes in position, a nut operating on the tubular member, said nut adapted to move the tubular member longitudinally of the hub, whereby the spokes are tensioned.

In witness whereof I have signed the foregoing specification.

CHARLES G. TATE.
